UNITED STATES PATENT OFFICE.

EMILY TRUMPLER, OF BROOKLYN, NEW YORK.

DRESS HANGER.

Application filed October 19, 1922. Serial No. 595,513.

To all whom it may concern:

Be it known that I, EMILY TRUMPLER, a citizen of the United States, residing at No. 253 Garfield Place, borough of Kings, city, 5 county, and State of New York, have invented a certain new and useful Improvement in Dress Hangers, of which the following is a specification.

The object of my invention is to provide 10 an inexpensive and convenient device for hanging and packing dresses and similar garments, that will preserve so far as possible the press and form of the dress and that will permit of the folding of the garment 15 about it for purposes of transportation with a minimum amount of wrinkling or creasing.

Briefly described the invention consists of a cardboard back, or body portion, of suitable length and width, with a curved top 20 and correspondingly curved and forwardly projecting rim, or shoulder, on which the garment rests. The device may have pockets for the storing of wearing apparel, such as gloves or hosiery intended to be worn with 25 the dress, and may likewise have a cover member designed to fold down over the back member.

Referring more particularly to the accompanying drawing, Fig. 1 is a front elevation 30 of the device showing the construction of the back member, and the front or cover member, folded down, and the means for joining said two members for suspending said device on a hook or nail.

Fig. 2 is a sectional longitudinal view of 35 the device.

Fig. 3 is an elevation similar to Fig. 1 without the cover or front member.

Referring more particularly to the accompanying drawing, *a* represents the back or 40 body portion of said device, being rectangular in form and of a length preferably of about two feet, with a curved top from which projects forwardly, *b*, a curved rim or shoulder member, which may be sewed, 45 glued, or otherwise permanently joined to *a*, and which is designed to support the dress or garment when hung about *a*, and to prevent or minimize wrinkling about the shoulders of the garment, when folded for transportation. Two small eyelets, *k*, are provided in the top of *a*, through which is inserted a string member, or a hook member 50 may be inserted for the purpose, thus providing a means for suspending said device on a hook or nail. The back member, *a*,

may be provided with one or more pockets, *c*, to carry items intended for use with the garment and most conveniently kept with it, said pockets being made simply by means of 60 sewing, gluing or otherwise suitably attaching an overlaying cardboard member to the body portion *a*. *d* represents a front or cover member, being rectangular in form, which may also be provided with a pocket, *f*, 65 and is likewise provided with two eyelets in the top, through which is passed the string, *g*, thus connecting the back and cover members. The function of the cover member is two-fold: It may serve to protect the dress 70 or garment while hung up, and, in packing more than one dress, or garment, it serves to prevent wrinkling and maintains the shape of the garments in transportation. When not in use, the cover member may be 75 turned back, over the top of, and allowed to hang behind, the back or body portion of the device. When it is desired to transport the garments, they are not removed from the hanger, as in the ordinary case, but are folded over and upon the body of the hanger, the shape of the garments being thus preserved and protected, and the cover member is turned forward over the garment. Thus 80 a rigid and easily handled package is formed, which may be conveniently placed in a trunk or suitcase. All parts of the device may be made of cardboard or any other material that has the like amount of rigidity, but cardboard is preferable because of its 85 inexpensiveness.

It may be observed that the curved rim, or shoulder member, may be either forwardly projecting or backwardly projecting, or both. In either case the same desirable result will be obtained.

It may likewise be observed that the convertibility of the device greatly increases its value as a time saver and an added convenience. For instance, when removing a 100 garment from a trunk or suitcase to a wardrobe, it may simply be done by hanging the device up without any intervening labor, and, vice versa, when desiring to pack a garment for transportation, the intervening 105 work of removing the dress from a hanger and then carefully folding same for packing is dispensed with. After removing the device from the point of suspension, the dress is simply folded about it and then placed in 110 a trunk or suitcase. It likewise saves people the necessity of having to take dress hangers

with them while travelling. Invariably people have to do this when travelling owing to the failure of hotels to provide these conveniences, but this is no longer necessary 5 when the above described device is used.

Having thus described my invention, what I now claim and desire to protect by Letters Patent is as follows:

In a garment hanger, a body portion on 10 which the garment is supported and comprising a substantially rectangular section having a curved upper edge, a rim conforming to and projecting laterally from said curved edge to provide a garment shoulder 15 receiving member, a rectangular cover sec-

tion of a size and shape approximating that of the body portion, and a flexible connector in loop form connected to the upper edge of the cover and passing loosely through openings in the body portion immediately below 20 the rim, the connector being of a length to permit the cover to be arranged to cooperate with the face or overlie the back of the body portion, said loop serving to draw the cover more or less tightly against the body portion when the device is suspended by the loop.

This specification signed this 13th day of October, 1922.

EMILY TRUMPLER.
